BALLOON PRINTING MACHINE

Filed May 18, 1932

UNITED STATES PATENT OFFICE

1,988,662

BALLOON PRINTING MACHINE

Hubert A. Myers, Toledo, Ohio

Application May 18, 1932, Serial No. 612,007

4 Claims. (Cl. 101—36)

My invention relates to printing machines and more particularly to a machine for printing inflatable bags or balloons or other compressible objects.

5 An object of my invention is to provide a printing machine which is adapted to print designs, figures, pictures or legends of any description, for example, advertising matter, on an inflatable rubber balloon in an efficient, rapid and economical manner.

10 Another object of my invention is to provide a machine for printing multiple color designs or figures or combinations of both in a rapid and efficient manner on an inflatable balloon.

15 I also contemplate printing with the machine of my invention other types of inflatable bags or compressible objects.

20 Other objects and advantages of my invention will readily become apparent throughout a reading of the following detailed description and accompanying drawing, in which:

Figure 1 is a perspective view of a balloon printing machine constructed in accordance with the principles of my invention;

25 Fig. 2 is an enlarged cross-sectional detail view of one of the rollers of my printing machine, taken on the line 2—2 of Fig. 1;

Fig. 3 is a rear end view of a portion of the printing machine, and

30 Fig. 4 is a wiring diagram illustrating the valve cut out hookup.

Referring now to the drawing in detail in which like reference characters designate like parts throughout the several views, I have shown in

35 Fig. 1 a printing machine embodying the principles of my invention in which a base 10 is suitably mounted on a pedestal 11. A pair of arched frames 12 and 13 each have a pair of legs 14 and 15 by which they are mounted on the base 10 on

40 opposite sides thereof. The frames extend vertically upward from the base 10 and support the operating mechanism. A plurality of printing drums 16, three are employed in the specific embodiment disclosed in the drawing, are rotatably mounted between the frames 12 and 13.

Axle shafts 17 extend through the drums on their axes and are fixed thereto. The ends of the axles 17 protrude beyond the ends of the drums 16 and are rotatably journaled in apertures 18 formed in the arches of the frames at equal distances apart. It is important that the apertures 18, in which these drum axles are rotatably journaled, are spaced equidistant from each other, see Fig. 3, to insure an equal distribu-

tion of pressure of the drums on the inflated balloon or object being printed. If three drums are employed, as disclosed in the specific embodiment shown in the drawing, they are spaced so that their axes of rotation are exactly 120 degrees apart. If four drums were employed they would be spaced exactly 90 degrees apart.

5 An inking roller 20 is provided for each drum 16 and these rollers extend co-axially with their respective drums and are in rotatable contact therewith. The rollers have shafts 21 which project beyond their ends and on which they are rotatably journaled in apertures 22 formed in the ends of arms 23 of the frames 12 and 13 which project outwardly therefrom.

10 The driving mechanism for the drums 16 is designed to rotate all of the drums one complete revolution simultaneously and includes a central gear 25 which is rotatably mounted at the rear end of the machine in a suitable manner on a bracket 26 which forms a part of the frame 13. Gears 27 which are of the same size as the gear 25 are provided for each drum 16 and one of them is fixed on the projecting rear end of each axle

15 shaft 17. Each gear 27 is in mesh with the central driving gear 25 and one complete revolution of the driving gear 25 will revolve each gear 27 and its respective drum 16 one complete revolution, since all of the gears are of the same size. A 20 pulley 28 is fixed to the gear 25 and is driven by a belt 29 connected with some suitable source of power not shown in the drawing.

25 Each drum 16 has its surface cut out arcuately longitudinally of the drum at 30 and when the drums are assembled in operative position in the machine the concavely arcuate cut out portions 30 are in registry to form an annular recess for the reception of a balloon or other spherical object to be printed.

30 The printing plates or cuts 31 are mounted on steel cylindrical sleeves 32, by soldering or in any other suitable manner. Transversely extending dovetailed steel splines 33 are fixed to the inner surfaces of the sleeves 32 adjacent the ends of the sleeves. It is to be noted that the sleeve 32 is not completely annular but is split and cut out

35 complementary to the cut out portion 30 of the drum. The dovetailed splines 33 are received in dovetailed slots 34 formed in the periphery of the drum 16 transversely thereof and near the cut out arcuate portion 30 as best shown in Fig. 2. The cylindrical sleeves 32 are therefore mounted on the drums by sliding them onto the drums from one end with the splines 33 sliding in the grooves 34. This facilitates the rapid change from one 40

set of printing plates or cuts to another since the cylinders may be quickly slipped on and off the drums and the printing plates or cuts will always be protected by the inner steel sleeve backing. 5 The splines 33 will prevent the sleeves from getting out of alignment and will insure alignment of the plates when slipped on the drums without further adjustment. The sleeves 32 are held on the drums, in operation, by a set of screws 35 10 which pass through slots 36 of the sleeves 32 and through the splines 33 into the drum. The slots 33 extend longitudinally of the drum and provide for longitudinal adjustment and alignment of the sleeves. 15 Means is provided to stop the operation of the mechanism upon one complete revolution of the drum which may be of any desirable form, the one illustrated in the drawing having a projecting stop 38, which may be formed on the 20 pulley 28 as shown in Fig. 3. A bell crank lever 39 is pivotally mounted in a bracket 40 secured to the base 10 directly below the axis of the pulley 28, the upper end of the bell crank being adapted to be in alignment with and engage the projecting stop 38. The other end of the bell crank 39 is bifurcated and pivotally secured at 41 to the upper 25 end of a rod 42, the lower end of the rod 42 being pivotally secured at 43 in the bifurcated end of a foot treadle 44 which is pivotally mounted at its center in a bracket 45. When the operator steps on the foot treadle 44 the bell crank 39 will be oscillated out of alignment with the stop 38 and the gear 25 and driven drums 16 will be permitted to rotate, the operator having released the foot 30 treadle during the rotation of the drums, the stop 38 will be engaged at the completion of one revolution and stop the mechanism. It is to be understood that this trip stop arrangement for permitting one complete revolution of the drums 16 is 35 only one form of control means which may be employed. 40

In the operation of the device of my invention a balloon 50 to be printed is slipped over one end of an air pipe 49 which supplies a predetermined amount of air to inflate the balloon. The operator inserts the balloon within the annular recess formed between the three rollers when the cut away portions 30 are in registry, as they will be at the beginning of the operation when the machine is idle, as illustrated in Fig. 1. The balloon 50 is then inflated to a predetermined size, the treadle 44 is tripped by the operator and the drums 16 are rotated one complete revolution as hereinbefore described. Upon the initial rotation of the drums 55 50 the annular opening formed by the cut away portions 30 will be reduced in size to the distance between the outer periphery of the drums as the portions 30 will be immediately rotated out of registry with one another as shown in Fig. 1. This 60 will compress the balloon and it will be displaced longitudinally of the rollers and the plates 31 will print the desired configuration, legend or design upon the surface of the balloon. At the completion of one rotation, the stop 38 will cause the 65 rollers to stop in registry with one another as they were at the commencement of the operation and the pressure will be relieved from the balloon and it may be removed from the central opening formed between the rollers by the cut away portions 30. It is apparent that an equal spacing 70 of the rollers relative to each other around the balloon is essential to produce an equal distribution of pressure during the printing operation to insure proper registry of the three plates as the 75 printing is done.

Multiple color work may easily be done in one operation or one rotative movement of the machine by having each of the three plates supplied with a different color ink from its respective ink applying roller 20; for example, one roller might be supplied with blue ink, another with red, and the third with yellow. 5

Means is provided in the balloon printing machine of my invention for automatically inflating the balloon to an exact predetermined size. This feature is important to insure proper printing of the balloon, equal distribution of pressure during the printing of the balloon and numerous other advantages which are readily apparent. I contemplate employing any suitable means for predetermining the amount of inflation of the balloon, the form shown in the drawing including a light flexible metal clip 51, one of which is secured to each drum 16 by a screw 52 and the spring clip is mounted in the recessed or cut away portion 30 of the drum. The clip is also arcuately shaped and adapted to engage contact points 53 and 54 when flexed as shown in Fig. 2. A pair of commutator rings 55 and 56 are mounted on the rear end of each drum 16. Suitable brushes 57 and 58 engage the respective commutator rings and the rings are concentric. The contact point 53 is connected to the inner commutator ring 55 by a wire 59 and the other contact point 54 is connected with the outer commutator ring 56 by a wire 60. The respective sets of commutator rings on each of the drums are connected in series with a source of electrical current 62 as shown in Fig. 4. A valve 63 is disposed in the air pipe 51 which supplies the air to inflate the balloon. The valve 63 is adapted to shut off the supply of air when actuated. A solenoid 64 is hooked up in the circuit and is connected with the valve 63 to actuate the valve 63 to a closed position when the solenoid is energized by a closing of the electrical series connection shown in Fig. 4. The circuit will not be completely closed unless all of the spring clips 51 are flexed to engage both of their respective contact points. In the operation of this means for automatically predetermining the size of the balloon, the balloon is placed between the rollers as shown in Fig. 1 when the arcuate recessed portions 30 are in central registry with each other. The balloon will be inflated through the air pipe 49 when the valve 63 is in open position and when the balloon has been inflated to the proper size, which may be predetermined by the positioning of the spring clips 51, the clips 51 will be flexed to engage the contact points 53 and 54 and complete the electrical circuit whereupon the solenoid 64 will be energized to actuate the control valve 63 and cut off the supply of air. 55

In this manner each balloon will be inflated to exactly the required predetermined size and the 60 spring clips will assist in aligning the balloon in exact central position relative to the printing drums. As hereinbefore stated, numerous other means may be employed to predetermine the exact amount of inflation of the balloon. 65

Rapid, economical and accurate printing of the inflated balloon is provided in the printing machine of my invention. The printing plates may be readily removed from the drums and replaced with other plates, requiring only a minimum of 70 time and effort to make the change, and the entire machine is simple and economical in operation and produces startlingly accurate results.

As many changes could be made in the above described arrangement, and many apparently 75

widely different embodiments of this invention could be made without departing from the scope thereof, it is intended that all matter contained in the above description or showing shall be interpreted as illustrative and not in the limiting sense.

What I claim is:

1. A machine for printing inflated balloons comprising at least three rotatable printing drums, the axis of each drum being spaced equidistant from the axis of each of the other drums to surround and support the balloon, each of said drums having an arcuate recess formed longitudinally in the surface of the drum to form an enlarged annular recess centrally between the drums for receiving the inflated balloon when the arcuate recessed portions of each drum are in central registry, and means to simultaneously rotate each drum one complete revolution to compress and print the balloon.
2. A device for printing inflatable objects having at least three rotatable printing elements disposed to surround and support the object to be

printed, means to inflate said object and means to predetermine the amount of inflation of the object to be printed.

3. A device for printing inflatable objects having a plurality of rotatable printing elements disposed to surround the object to be printed, an air line to supply air to inflate the object, a valve in said air line and means to automatically close the valve when the object has been inflated to a predetermined size.

4. A device for printing inflated balloons having a plurality of rotatable printing elements disposed equidistant from each other surrounding the balloon to be printed, each rotatable element having a portion of its outer surface cut away to form a central recess between the elements when they are rotated to a position with the cut away portions in central registry with each other, means to inflate the balloon and means to automatically control the amount of inflation of the balloon.
